LAWRENCE S. CAMPBELL, OF KANSAS CITY, MISSOURI.

GAS-GENERATING OIL-BURNER.

1,300,246.

Specification of Letters Patent. Patented Apr. 15, 1919.

Application filed August 14, 1918. Serial No. 249,922.

To all whom it may concern:

Be it known that I, LAWRENCE S. CAMPBELL, a citizen of the United States, residing at Kansas City, in the county of Jackson 5 and State of Missouri, have invented a new and useful Improvement in Gas-Generating Oil-Burners, of which the following is a specification.

My invention relates to gas generating 10 burners for oil stoves, and the objects of my invention are, first, to provide a cheap, durable, and economical gas generating burner having facility for generating a fuel gas from petroleum oil, and which may be applied to furnaces and stoves, and second, to 15 provide the burner with facility for obtaining perfect combustion of the generated gas to prevent accumulations of carbon and soot.

I attain these objects and other advantages by means of the mechanism and combination of parts illustrated in the accompanying drawing in which—Figure 1, is a vertical elevation of a burner embodying my 20 invention, and showing the same applied to a hot air furnace; Fig. 2, is a bottom view of the retort, a part of my invention, and taken on the line II—II, in Fig. 1, and showing the radial ribs and vents for gas; Fig. 3, is a vertical section through the complete 25 burner, on the line III—III, in Fig. 1, and showing the gas generating diaphragms, a part of my invention; Fig. 4, is a top plan view of the supporting member; Fig. 5, is 30 a view of the inner side of the saucer member of the diaphragms; Fig. 6, is a top plan view of the distributing plate member forming part of the diaphragms, a part of my 35 invention; Fig. 7, is a top plan view of one 40 of the diaphragms, and showing the indentations therein to space the same from the saucer member; Fig. 8, is a vertical section of the diaphragm, on the line 45 VIII—VIII, in Fig. 7, and Fig. 9, is a view 50 of the inner side of the lower section of the retort.

Similar numerals of reference refer to corresponding parts throughout the several views.

The numeral 1, indicates a gas generating 55 oil burner which embodies my invention, and which is mounted on grate bars 2, in the fire pot 3, of a furnace 4, and operatively connected with an oil supply pipe 5, the latter being connected with a source of oil, not shown, and adapted to supply oil

to the burner by gravity. The burner consists of an inverted cup-shaped section 6, which is demountably secured on the rim of a similar section 7, the assembled sections 60 forming a retort having a chamber 8. The exterior sides of the sections 6 and 7, are provided with radially extending ribs 9, which project a little distance to provide additional heat conducting and radiating 65 surfaces. An annular vertically extending flange 10, is formed at the inner edge of the rim of section 7, and a substantially similar flange is formed at the outer edge of the section 6, the latter being adapted to overlap the former with a suitable degree of friction to hold the sections operatively assembled. A stud 11, is formed integral with section 6, and is adapted to receive a perforated plate or other device for spreading 70 and deflecting the flame of the burner. A boss 12, is formed on the lower side of section 7, and is provided with a hole 13, which is bored to present an oblong or elliptical appearance for the purpose of engaging a 75 pipe, and permitting communication with the interior of the retort alongside of the pipe. The lower portion of the boss is reduced circumferentially and provided with slotted orifices or vents 14. A vertically extending pipe 15, is provided at a suitable intermediate point with a washer 16, and which is adapted to receive and support the 80 retort portion of the burner, the upper portion of the pipe being extended through the 85 hole 13, penetrating the chamber 8, to closely adjacent its top. A supporting member 17, comprising a wheel 18, having an annular bead 19, inwardly adjacent the inner edge of its rim, a hub 20, and spokes 21, radiating 90 therefrom, is adjustably mounted the pipe 15, a suitable distance below the washer 16, and is adapted to lodge and lie horizontally upon the grate bars 2, in the furnace and thereby hold the burner in vertical position. A catch basin 22, is secured 95 on the lower portion of the pipe 15, in such a manner that it shall be positioned in the ash pit 23, of the furnace. An outlet 24 is provided in the catch basin for the passage 100 of waste oil. A series of metallic diaphragms 25, are demountably mounted on the pipe 15, within the chamber 8, and comprise saucer-shaped members 26, provided with central openings 27, adapted to receive 105 the pipe 15, and having their borders up-set and forming annular flanges 28, and per-

forations 29, in the bottoms of the saucers adjacent the up-set flanges; the inner sides of the bottom portions of the saucers are formed concaved. Circular convexed disks 5 30, having diameters less than the diameters of the saucers are mounted on the pipe 15, and are received by the saucers, the disks being provided with indentations 31, to form ribs 32 on their lower sides to hold 10 the disks spaced apart from the saucers and with central openings 33, having their borders up-set and forming flanges 34. The diaphragms organized as above described, are mounted one after the other on the pipe 15, until the chamber 8, is substantially 15 occupied by them, the flanges 34, on the disk of the lowermost diaphragm supportingly engaging the inner side of the next above saucer member, continuing thus to pile the 20 diaphragms. The uppermost disk on the uppermost diaphragm is secured on the pipe in any suitable manner for the purpose of holding the diaphragms operatively assembled.

25 To apply my invention, the wheel 18, is secured on the pipe 15, at the desired point thereon, and the washer 16, is slidably mounted there-above a suitable distance and best adapted for receiving and supporting 30 the retort of the burner, the washer being held in place by any suitable detaining means, in this instance, by a collar 35, which is provided with a set screw 36. The cup section 7, is then loosely mounted on the 35 pipe, so that the lower end of the boss 12, having the vents 14, is received and supported by the washer 16. The diaphragms 25, are then piled, one on the other, and mounted on the portion of the pipe penetrating 40 the chamber 8, the disk of the uppermost diaphragm being secured on the pipe, in the manner already described. The oil supply line is then connected with the pipe 15, and is admitted in regulated quantity, 45 in the customary manner. The oil spills from the upper end of the pipe 15, upon the disk of the uppermost diaphragm where, because of the convexity of the disk, the oil gravitates to the edge thereof and is spilled 50 into the saucer member of the diaphragm, and particularly through the depressions caused by indentations 31, the oil gravitating along the concaved bottom of the saucer and spilling through the perforations 29, 55 therein, into and upon the next below diaphragm, and thereafter continuing in like manner through the other diaphragms, finally reaching the bottom of section 7, and gravitating through the elliptical hole 13, 60 and on the outer side of the pipe 15, therein, and out of the vents 14, where the oil is ignited and allowed to burn, thereby heating the retort and the diaphragms therein to such a degree that the oil therein and thereon 65 will be converted into a combustible gas,

and which will ultimately be forced out of the vents 14, and ignited.

When the gas escapes from the vents 14, the air passing inwardly through the wheel of the supporting member, mixes with the 70 gas and, thereby, an intense flame is produced which heats the furnace walls without accumulations of carbon and soot.

The burner device is applied to the furnace, by passing the lower portion of the 75 pipe 15, downwardly through the grate openings and bringing the lower side of the supporting member 17, to bear on the grate bars 2, and the saucer or catch basin 22, attached, the pipe 15, being then connected 80 with the oil supply line. Asbestos or any other suitable material is lodged on the grate bars, between the supporting member and the furnace wall, so that the air shall be admitted to mix with the gas, through the 85 wheel 18, between the spokes thereof. The air and gas mix automatically and the mixture, when ignited, produces intense heat, which effects a heating of the furnace and a heating of the retort and, thereby, the diaphragms are maintained in heated condition and the oil thereon converted into gas without delay.

Having described my invention what I claim is—

1. In a gas generating oil burner, the combination, of a cup-shaped section provided exteriorly with radial projecting ribs and with an extension having an opening communicating with the section, an inverted cup-shaped section demountably mounted on said first mentioned section and provided exteriorly with radial projecting ribs and forming with the latter a retort, a pipe penetrating said retort and having a washer 95 slidably mounted thereon and adapted to supportingly engage the retort, diaphragms mounted on said pipe within the retort, said diaphragms comprising perforated saucer-shaped members provided with central openings and with vertical annular flanges at the borders of the openings and convexed disks supportingly engaged by said saucer-shaped members and provided with central openings and with vertical annular flanges at the borders of the openings and adapted to receive and support the saucer-shaped members, and means carried by said pipe for supporting the burner in vertical position.

2. In a gas generating oil burner, the combination, of a cup-shaped section provided with an extension on its lower side having an opening communicating with the cup-shaped section, an inverted cup-shaped section demountably mounted on said first mentioned section and forming with the latter a retort, a pipe penetrating said retort and having a washer slidably mounted thereon and adapted to supportingly engage the retort, and diaphragms mounted on said 100 105 110 115 120 125 130

pipe within the retort, said diaphragms comprising perforated saucer-shaped members having central openings and annular vertical flanges at the borders of the openings and convexed disks supportingly engaged by said saucer-shaped members and provided with central openings and with

vertical annular flanges at the borders of the openings.

Kansas City, Mo., August 9th, 1918.
